(57) **CLAIM**

The ornamental design for a display panel or screen or portion thereof with animated graphical user interface, as shown and described.

DESCRIPTION

FIG. 1 is a front view of a display panel or screen or portion thereof with animated graphical user interface showing my new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof; and,

FIG. 8 is an eighth image thereof.

The broken lines illustrate the display panel or screen or portion thereof and form no part of the claimed design.

The appearance of the animated graphical user interface sequentially transitions between the images shown in FIGS. 1-8.

The process or period in which an image transitions to another forms no part of the claimed design.
